the fixed signal generator 22 is directly coupled to the gimbal 19 of the vertical gyro so it will be necessary to limit the displacement of the aircraft about the pitch axis B-B.

The aileron 2 and the elevator 4 are controlled by solenoids 14 located on the aileron and elevator signal circuits 7, 8 and 9, 10 respectively which are connected respectively to the input terminals of the aileron and elevator servo amplifiers 16, 17.

In the aileron and elevator signal circuits there are connected the stator windings of the follow-up signal generators 21 and 24 which are shown as identical in construction to the bank and pitch signal generators 21 and 22 previously described. The outputs of the follow-up signal generators are mechanically coupled to the output shafts of the servomotors as indicated by the dotted lines 25, 26, 27, 28, 29, 30, 31, 32, 33, 34, 35, 36, 37, 38, across the secondary winding of transformer 29. A current will flow in the circuit which can be traced from terminal 41 through resistor 47 (which offers a low resistance) through resistor 48, resistor 49, rectifier 50 (which also offers a low resistance) to terminal 42. At the opposite end of the secondary winding, it will be noted that a low resistance path therefore exists between the mid-tap 34 and the junction of resistors 48 and 49. This low path resistance is also in series with the output resistor 59 which may be traced from terminal 33 through the mid-tap 35, through the upper half of the secondary winding to terminal 33, rectifier 58 (which offers a low resistance) and the junction of resistors 48, 49. Since the resistance of the output resistor 59 is very high compared to any other resistance in the foregoing circuit, it will then be clear that substantially all of the potential between terminals 33 and 35 will appear across the output resistor 59. The output of the opposed rectifier 58, substantially no current will flow in the circuit connected across the secondary winding between terminals 34 and the mid-tap 35.

Having now examined the foregoing circuit when the polarities of the various components are taken as above explained, let us examine the case where the polarities at the secondary winding of the transformer 29 are reversed. It will then be instantaneous polarities at terminal 33 and at terminal 34 will remain unchanged, but now, the instantaneous polarities at terminals 35 and 36 will be assumed to be negative while that at terminal 42 will be assumed to be positive. Due to the relatively high impedance of the oppositely disposed rectifiers 47 and 58, substantially no current will now flow in the chopper circuits which can be traced from terminal 42, rectifier 58, resistors 48 and 49, rectifier 47, and terminal 4. Whatever voltage drops there will exist almost entirely across the high resistances of the rectifiers 50 and 47. According to the chopper circuit may now be considered as substantially a very high impedance connected between the mid-tap 43 and the junction of resistors 48, 49. This high

impedance will be connected across the secondary winding of transformer 29. The voltage across the secondary winding of transformer 29 is such that, since a positive voltage is applied to resistor 59, then the voltage across the secondary winding of transformer 40 will produce a negative voltage across the output resistor 59. The combined signal at resistor 59 will be a sine wave, which is always of the same polarity regardless of the polarity of the input. The output of the output resistor 59 will be connected to the input of the rectifier 58 and whose amplitude will remain proportional to the input. In terms of aircraft attitude, this means that, irrespective of whether the aircraft is banked to the left or to the right, there will appear across the output resistor 59 a voltage which is always proportional to the banked signal and which is always of the unchanged polarity regardless of the polarity of the input. The output of the output resistor 59 is then inserted in the elevator signal circuit so as to provide an additional signal which will correct the pitch angle of the aircraft during turns so as to counter the loss of vertical lift.

In order for the human pilot to manually effect a change in the pitch angle of the aircraft, it is operated by means of a knob 60. Displacement of the knob 60 in one direction or the other causes a corresponding change to be made to be introduced in a well known manner into the aileron signal circuit from the common source 16, 17. This change is caused by a variable voltage source 61 in one direction or the other depending upon the polarity of the bias voltage since the aircraft may be banked in one direction or the other to reduce to zero the resultant displacement voltage fed into aileron signal circuit.

It is often the pitch of the aircraft either during straight flight or during turns, there is provided a pitch control 61. By manipulation of a suitable control knob 62, an adjustable bias voltage is introduced in series with the signal generator 22 thus causing a change to take place in the pitch attitude of the aircraft.

In operation, let it be assumed that the pitch control and pitch control knobs 60 and 62 are placed in the null position shown. If the aircraft becomes displaced about the bank or pitch axes

control knob 60 is displaced to the left and just the reverse of the above-described operation will be the case. The signal introduced by the signal introduced into the elevator signal circuit from circuit 27 will remain the same as before, tendency to move the elevator in a downward direction to counteract for the loss of vertical lift during the left bank.

It may be noted that some relationship between the aileron signal voltage and the voltage transmitted to the circuit 27 other than a proportional one will be required according to the particular dynamic response characteristics of the particular aircraft. If it is desired to increase the relationship between the signals it will be understood of course that this can be accomplished by many suitable means readily known to those skilled in the art.

The particular arrangement shown and described is, of course, merely illustrative and it will be readily appreciated from the above that the counteracting circuit 27 may take its input from any suitable point in the bank channel. Likewise while the output of circuit 27 may be introduced at other points in the pitch channel, it being evident that the counteracting circuit 27 is intended to introduce the change in an additional signal voltage which varies as a function of some signal in the pitch channel in the aileron loop, thereby to offset the loss of vertical lift of the aircraft during banking. In the copending application of M. M. Bunting, Serial No. 38446, filed July 17, 1948 and titled "Aircraft Maneuvering Control," the circuit 27 has performed very satisfactorily when

30 circuits, a signal about the bank axis of said aircraft, and to the other of said output circuits, a signal about the pitch axis of said aircraft in accordance with the respective displacements of said aircraft about the bank and pitch axes, a servomotor for controlling the aileron in a direction about its pitch axis in response to signals from the pitch output circuit in bank and pitch control or each receiving a command from said output circuits for manually varying the normal bank and pitch signals, a counteracting circuit having an input 40 receiving a signal from the output of said bank control means, and further comprising two secondary windings, a copper circuit connected to each of said windings, a switch joining the outputs of said chopper circuits whereby to provide a unidirectional signal irrespective of the polarity of the signals to be supplied to the servomotor, and a resistor being serially connected with the output of the pitch signal control means whereby to introduce a negative feedback signal having a magnitude a signal tending to cause an increase in the vertical lift of said aircraft while banking.
